UNITED STATES PATENT OFFICE.

FRANCIS M. BISSELL, OF COLDWATER, MICHIGAN, ASSIGNOR OF ONE-HALF
TO JOHN STEARNS AND ANDREW J. McGOWAN, OF SAME PLACE.

FANNING-MILL.

SPECIFICATION forming part of Letters Patent No. 253,968, dated February 21, 1882.

Application filed July 20, 1881. (No model.)

To all whom it may concern:

Be it known that I, FRANCIS M. BISSELL, a citizen of the United States of America, residing at Coldwater, in the county of Branch 5 and State of Michigan, have invented certain new and useful Improvements in Fanning-Mills; and I do hereby declare the following to be a full, clear, and exact description of the invention, such as will enable others skilled in 10 the art to which it appertains to make and use the same, reference being had to the accompanying drawings, and to letters or figures of reference marked thereon, which form a part of this specification.

15 The present invention relates to that class of fanning-mills for cleaning and separating grain in which an upper laterally-shaking shoe is employed for removing oats, chess, and other impurities from the grain, a lower 20 longitudinally-shaking shoe being employed for separating the grain according to size and quality.

The object of the invention is to furnish a fanning-mill of the class above mentioned in 25 which the mechanism for actuating the cleaning and separating shoes is greatly simplified, so as to cause these parts to run more easily than heretofore, provision being also made for retaining the riddles of the upper shoe without 30 the aid of the customary grooves in the sides of said shoe.

My improvements consist in the construction and combination of parts, which will hereinafter be more fully described, and then set 35 forth in the claim.

In the drawings, Figure 1 is a side elevation of a fanning-mill constructed according to my invention. Fig. 2 is a vertical longitudinal section of the same. Fig. 3 is a bottom view of 40 the lower separating-shoe; and Fig. 4 is a front elevation of the machine, showing the transverse rock-shaft carrying spur-segments for imparting a reciprocating movement to the lower shoe.

45 The casing or frame of the machine (designated by the letter A) is of any approved construction, and has a fan chamber or box, B, at its front end. A feed-hopper, C, on the top of the frame is provided with a suitable gate 50 or slide for regulating the discharge of the grain through the throat of said hopper.

A laterally shaking or vibrating shoe, D, is located below the feed-hopper and operates through the slotted side walls of the mill-casing. The shoe D is composed of two side 55 boards and a front connecting-bar, having the stationary section of a "chess" or feed board, E, arranged in rear of said bar. An extension or movable section, F, of the board E is fitted in suitable grooves or ways in the side boards 60 of the shoe, and is capable of being pushed under said board E, increasing the area of the screening-surface of the riddle or screen fitted in the shoe D. The board F, when drawn out from under the board E, constitutes an extension 65 of the latter, and the area of the screening-surface is decreased when the parts are in the position mentioned.

The shoe may contain an ordinary wire riddle of any desired size, according to the kind 70 of work to be performed, or else I may employ a combination zinc or metallic screen, G, consisting of three metal plates having circular openings, and fitted in front and side bars comprising a holding-frame.

75 The wire riddle and the combination metal screen just mentioned are used interchangeably, and are retained between the side boards of the shoe through the medium of transverse tie and clamping rods or bolts H, having one 80 or more screw-threaded ends, and nuts h, fitted on the latter. It will be obvious that by loosening said nuts the riddle or screen used can be adjusted vertically, so as to change the angle of inclination of the same.

85 The customary grooves made in the side boards of a shaking-shoe for securing the sieves are in the present instance dispensed with, as the tie-rods suffice to clamp the sieve or screen between the side boards of the shoe. A screen 90 provided with circular holes is specially designed for removing oats, barley, and other elongated grains or seeds from wheat, as the formation of the holes will only allow the wheat to pass through the same, all other materials being caused to pass off at the tail-end of the screen.

95 The grain assorting or separating shoe I is arranged below the upper cleaning-shoe, and is inclined toward the front of the machine, so 100 as to discharge its contents away from the tailings of the upper shoe. The shoe I is of a box-

like form, and has a series of sieves, J, fitted therein, which gradually diminish in length from the top to the bottom of the shoe. The mesh-work of the screens also varies in size, 5 the uppermost screen being the coarsest and the others gradually increasing in fineness to the bottom of the shoe. The top sieve has guide-strips e at its rear end, which converge toward a throat or opening, f, in the end of 10 the shoe, so as to deliver the tailings of said top sieve through said opening. The tailings of the second sieve are received by a gutter or trough which extends through the side of the shoe, and the grain which passes through said 15 second sieve is received by the next one below, which in the present instance discharges its tailings into a receptacle or trough, which also receives the grain passing through the rear portion of the second screen. The bottom 20 of the receptacle receiving the grain from two screens in the manner stated is provided with a slit, and a drawer or box, K, located below the latter, receives the grain. The fourth screen discharges its tailings into another receptacle, N³, and the latter also receives the grain screened through the rear portion of the third screen. A drawer or box, K', is located 25 below the last-mentioned receptacle for receiving the grain passing from the same.

30 The number of screens employed depends upon the quality or size of the grain, and obviously the pockets or receptacles in the shoe must correspond in number with said screens, so as to receive the tailings of one screen and 35 the material screened through the rear portion of the screen next above.

A reciprocating movement in a longitudinal direction is imparted to the shoe I through the medium of a transverse rock-shaft, L, which 40 is journaled in suitable bearings at the front of the mill-casing, and has spur-segments M keyed or otherwise secured thereto. These spur-segments mesh into rack-plates N, let into or secured to the under side of the shoe I 45 at the sides thereof. The rock-shaft L is actuated through the medium of a vertical rod, O, which is connected with a crank-arm, f², of the rock-shaft, and with a wrist-pin, g, on an end pinion, h, of the blast-fan P. Said pinion gears into a large spur-wheel, Q, to which 50 is applied a driving-crank or other device for communicating motion thereto.

A longitudinal rod, R, connected with the wrist or eccentric pin g, extends to the rear of the machine, and is connected with a bell-crank lever, S, located therat. A link, T, attached to said bell-crank lever, is connected 55 with the upper shoe for imparting a shaking motion thereto. Plate or leaf springs U, bearing against the outer sides of said shoe, and attached to the mill-casing, serve to return the shoe or give the requisite jarring movement thereto.

A wind-board or blast-regulating board, V, is journaled in the mill-casing below the upper sieve-shoe, and can be raised or lowered for throwing the blast with greater or less force upon the upper shoe in a manner common to other fanning-mills. A ratchet-and-pawl device, W, is employed for retaining the wind-board in various positions. The feed-board of the upper shoe is also designed to concentrate the blast upon a reduced area of the screen, so as to cause it to act with greater force upon the material delivered thereto. For example, 75 when chess or other light seeds predominate in the grain the adjustable board is drawn backward for reducing the screening area of the screen.

Mechanism for imparting a longitudinal shaking movement to the lower separating shoe is used, in connection with means for imparting a vertical jarring motion to said shoe, for preventing the clogging of the meshes of its screens. The means employed for the object stated comprise rollers X, located at each side of the mill-casing, and depressed or undulating plates Y, let into the under side of the shoe. Said plates in passing over the rollers, during the reciprocation of the shoe will cause 90 the latter to rise and fall.

I am aware of the English Patent No. 413, granted A. D. 1860, which illustrates a reciprocating separator-shoe operated by means of a rock-shaft carrying a segment which meshes 95 into a rack-plate applied to an angular block located at the upper end and on the under side of a shoe which is inclined throughout its entire length. In my invention two rack-plates are applied to the lower horizontal portion of a reciprocating shoe, and the latter is inclined from a point at or near said rack-plates to the upper or feed end of the shoe, where devices are located for imparting a jarring movement to the shoe without throwing 100 out of gear the devices for effecting the reciprocating movement of the shoe.

Having thus described my invention, what I claim, and desire to secure by Letters Patent, is—

In a fanning-mill, the combination of the shaking shoe having a series of inclined sieves, and a horizontal bottom section or floor provided with rack-plates, and an upper inclined section or floor carrying undulating or 115 depressed plates, with the rock-shaft provided with spur-segments engaging with the rack-plates, and the mill-casing having rollers engaging with the depressed plates, as and for the purpose herein set forth.

In testimony whereof I affix my signature in presence of two witnesses.

FRANCIS M. BISSELL.
